UNITED STATES PATENT OFFICE.

ROBERT G. PECK AND ALBERT BROWN, OF CHICAGO, ILLINOIS, ASSIGNEES TO THE ARIDOR COMPANY, OF CHICAGO, ILLINOIS, A CORPORATION OF ILLINOIS.

DISPLAY RECEPTACLE.

Application filed December 3, 1923. Serial No. 678,109.

The present invention aims to provide an improved receptacle particularly adapted, for example, for use as a display receptacle for hard candies.

5 For illustration, one desirable form of display receptacle containing an embodiment of the invention is shown in the annexed drawings, by reference to which the invention will be readily understood.

10 In said drawings;

Fig. 1 is a side elevation of the illustrative receptacle.

Fig. 2 is a side elevation of the mouth of the receptacle with its door or closure in 15 open position.

Fig. 3 is an inner face view of the receptacle closure, together with parts of a collar to which the closure is hinged, and showing the mouth of the receptacle in cross 20 section.

Fig. 4 is a horizontal section through the mouth of the receptacle and its closure.

Fig. 5 represents a detail of the specific closure shown.

25 The illustrative embodiment of the invention shown in the drawings is a transparent receptacle for use on a store counter for displaying contents such as for example as hard candies. The receptacle is shown having a

30 front display end, while the rear end of the receptacle may be opened to permit insertion of a candy scoop for dispensing the candy to customers.

Said receptacle is represented as a jar 1 of 35 transparent glass, arranged in recumbent position, and formed to provide a display head 2 of extensive surface at the end of the jar opposite its mouth.

40 By supporting the neck 3 of the jar in a rack or stand 4, the jar is held at an appropriate inclination to cause the candies therein to tend to gravitate toward and remain massed in the space adjoining the display head 2, through which as well as through 45 the transparent top and sides of the receptacle the candies are exposed to the view of customers standing before the counter on which the receptacle is placed.

50 The mouth of the receptacle is closed by a door 5 herein represented as a hinged jar cap which is held pressed against a gasket 6 to maintain a tight closure. In this in-

stance the door is self-opening by the action of a spring hinge 7. It is held closed by a spring-actuated latch 8 which catches over 55 a bead 9 formed on the sheet metal rim of the jar closure or door. In closing the door, the bead 9 will coact with the bevelled end of the latch to force back the latch, which will then snap over the bead and retain the 60 door closed against the gasket 6. For retracting the latch, it is shown provided with a handle or knob 10.

The latch housing 11 and the door hinge 7 are attached to a collar 12 surrounding 65 and affixed to the neck of the jar. This collar may be an integral part of the rack or stand 4, which may be formed as a plate of sheet metal having an opening to receive the neck of the jar. Lugs 13 attached to the 70 collar carry screws 14 to engage behind a shoulder 15 on the neck of the jar for affixing the collar thereto. If desired these lugs may be resilient to permit snapping the screws over the shoulder 15. Thus the 75 metallic stand with the door and fixtures carried thereby may be conveniently applied by inserting the collar 12 over the jar neck and tightening its attaching screws, or snapping the collar into place if the lugs 12 are 80 made sufficiently resilient for that purpose.

Hard candies when exposed to humidity become sticky and dull looking. To maintain an attractive display, the candies should be kept dry and crisp, in order to preserve 85 their solidity, color and glint or lustre and to prevent objectionable sticking of the candies to one another or to the interior surfaces of the display receptacle. Such a display may be obtained in the illustrative receptacle, the interior and contents of which are maintained in dry condition by the action of a hygroscopic medium 16 (Fig. 4) represented by a pad or cake of porous moisture absorbent and attracting material, e. g. 90 a baked mass of infusorial earth impregnated with calcium chloride and containing asbestos fibres as a binding material.

The hygroscopic pad is shown mounted in the jar closure or door 5, being fitted in a 100 chamber provided between the outer wall of said closure and a flanged plate 17 removably secured therein. A bolt 18 passing through a central hole in the hygroscopic

pad centers the pad in its chamber and secures the parts of the door structure together.

Through the perforations 19 in the plate 17, the air in the display receptacle may circulate through the hygroscopic pad chamber in contact with and through the pores of the hygroscopic substance, which will attract and absorb any moisture in the receptacle and keep its contents thoroughly dry.

By locating the hygroscopic pad adjacent the mouth of the display receptacle, it may exercise its dehydrating action at the most advantageous point, i. e. at the end of the receptacle remote from the display end and which is first affected by the admission of atmospheric moisture.

Associated with the perforated plate 17 is a shutter represented by a plate 20 having perforations 21 normally in registration with those of the plate 17 but adapted to be moved out of registration therewith. This shutter plate, rotatably mounted on the central post or bolt 18, is shown in this instance fitted to the inner side of the plate 17, and is utilized as the inner face of the receptacle door which closes against the gasket 6 as shown in Fig. 4.

When the receptacle door is opened, the shutter 20 is turned to the position shown in Fig. 2, moving its openings or perforations out of registration with those of the plate 17 so as to close the hygroscopic pad chamber. This is accomplished by means represented by a spring 22 shown coiled about the central bolt 18 and having one arm bearing against a stud 23 on the shutter plate and the other arm bearing against a stud 24 on the plate 17, which stud projects through a short arcuate slot 25 in the plate 20 and limits the turning movements thereof.

Upon closing the receptacle door, the shutter plate 20 is restored to the normal position shown in Fig. 3, with its perforations registering with those of the plate 17, thus reopening the hygroscopic pad chamber to communication with the interior of the display receptacle. The means shown for this purpose comprises an arm 26 protruding from the mouth of the receptacle, as shown in Figs. 2 and 4, and adapted to pass through arcuate slots 27 and 28 in the respective plates 17 and 20. An inclined edge 29 of said arm 26 coacts with a hard metal-ware piece 30 at one end of the slot 28 to turn the shutter plate against the resistance of the spring 22, or in other words to move the shutter by camming action from the position shown in Fig. 2 to that shown in Fig. 3.

As shown in Fig. 4, the arm 26 may be provided by a sheet metal strip 31 attached to the collar 12 and bent over the mouth of

the receptacle, the gasket 6 being slotted to permit the insertion of said sheet metal strip therethrough.

From the foregoing description, it will be seen that the chamber containing the hygroscopic pad is automatically closed when the receptacle door is opened, and is reopened to communication with the interior of the receptacle when the door is shut. Thus while the receptacle is open for dispensing candy, the hygroscopic pad is protected from absorption of atmospheric moisture, retaining its strength and efficiency to restore effective dehydrating conditions in the receptacle after it is closed. In other words, the action of the hygroscopic medium is exerted only upon the volume of air admitted to the receptacle itself. This promotes rapid and thorough dehydration, the action of the hygroscopic pad being unimpeded by surplus moisture absorption. Furthermore, by protecting the hygroscopic pad from moisture absorption other than that in the air admitted to the receptacle, the pad may be used for a prolonged period without becoming sufficiently wet to require replacement by a dry pad.

The construction described provides a practicable, convenient and attractive receptacle appropriate for a bright display of colored hard candies, for instance, and which may be opened from time to time for dispensing the candy while still effectively maintaining the efficiency of the receptacle to preserve the candies in dry and lustrous condition as is necessary for an attractive display.

Obviously the present invention is not limited to the particular embodiment thereof herein shown and described, since details of construction, form and arrangement may be modified. Moreover it is not indispensable that all the features of the invention be used conjointly, since they may be advantageously used in various different combinations and sub-combinations.

We claim as our invention:

1. A display receptacle comprising, in combination, a transparent container for displaying an enclosed mass of hard candies; a door for opening and closing the receptacle; a hygroscopic medium protected from the atmosphere while the receptacle is open, and communicating with the interior of the receptacle when closed, for conditioning the interior of the receptacle to keep the candies dry and glistening for effective display; and means for covering and uncovering said medium when the receptacle is open and closed respectively.

2. A receptacle for displaying hard candies comprising a transparent container therefor having means conditioning its interior to preserve the hardness and glint of the candies, and having means operative

during opening of the receptacle for maintaining the efficiency of said first named means to establish interior conditions for preservation of the candies as aforesaid 5 when the receptacle is closed.

3. A display receptacle comprising a transparent candy container having a hygroscopic medium conditioning its interior to keep the candies dry and lustrous for attractive display, and having means protecting said medium from the atmosphere when the container is opened.

4. A display receptacle comprising, in combination, a container having a closure and a transparent display portion beyond the closure; means adjacent the mouth of the receptacle for holding a hygroscopic medium; and means operated by the opening and shutting of the closure to maintain said medium covered for protection from the atmosphere when the closure is open and to expose said medium to communication with the interior of the receptacle when the closure is shut, whereby said medium will 20 be effective upon closing the receptacle to establish conditions for preservation in dry and lustrous condition of candies displayed in said receptacle.

5. A candy display receptacle comprising, in combination, an elongated substantially horizontal container having a display end; a closure therefor at the opposite end; hygroscopic material mounted proximate said closure; and means protecting said material from exposure to the atmosphere when said closure is opened.

6. A display receptacle comprising, in combination, a recumbent transparent jar having a display end opposite its mouth; a 40 plate having an opening to receive the neck of the jar, said plate providing a collar surrounding and affixed to the neck of the jar, and having a rest by which the jar is supported at an inclination; a gasket on the mouth of the jar; a door hinged to said collar; and a latch mounted on said collar for holding the door closed against said gasket.

7. A display receptacle comprising, in combination, a recumbent transparent jar; a collar having an opening to receive the neck of the jar, said collar adapted to be slipped over the jar neck; a rest integral with said collar by which the jar is supported at an inclination; a jar closure and fastening therefor carried by said collar; and attaching means carried by said collar cooperative with the jar neck for securing the collar in place; whereby the rest with the closure and accompanying fixtures may be conveniently applied by inserting the collar over the jar neck and securing the attaching means therefor.

8. A display receptacle comprising, in combination, a transparent container hav-

ing a closure; a hygroscopic medium mounted in said closure; and means operative to cover said medium to exclude it from the atmosphere when the closure is open and to uncover said medium for exposure to the 70 interior of the container when the closure is shut.

9. A display receptacle comprising, in combination, a transparent container having a door or closure; said door having a chamber for a hygroscopic medium; and means closing said chamber when the door is open and opening said chamber to communication with the interior of the receptacle when the door is shut.

10. A display receptacle comprising, in combination, a transparent container having a door or closure; a chamber for a hygroscopic medium communicable with the interior of the receptacle; and means maintaining said chamber open while the receptacle is closed and operative to close said chamber when the door is opened.

11. In a display receptacle, the combination with the receptacle door, of a chamber for a hygroscopic medium communicable with the interior of the receptacle; a shutter closing said chamber when the door is open; and means for operating the shutter to open said chamber when the door is shut.

12. In a display receptacle, the combination of a receptacle door having a chamber for a hygroscopic medium; a shutter closing said chamber when the door is open; and means operating said shutter to open said chamber to communication with the interior of the receptacle when the door is shut.

13. A container having, in combination, a closure; a hygroscopic pad mounted in the closure; and movable means operative to 105 cover said pad to exclude it from the atmosphere and for uncovering said pad for exposure to the interior of the container.

14. A jar having, in combination, a removable closure; a holder for hygroscopic 110 material mounted in said closure; and means to cover and protect said material from the atmosphere, said means movable to position to expose said material so that the same may operate on the interior of the jar when the 115 closure is shut.

15. A candy jar having, in combination, a closure; a chamber for hygroscopic material in the closure; and a rotary shutter for opening and closing said chamber to expose said 120 hygroscopic material in the jar and to shut off said material from the air when the closure is removed.

16. A receptacle having means for opening and closing it and having a hygroscopic medium and means whereby said medium is automatically shut off from the air when the receptacle is opened and automatically exposed in the receptacle when the receptacle 125 is closed.

17. A receptacle having, in combination, a door for opening and closing the receptacle; a hygroscopic medium protected from the atmosphere while the receptacle is open, and communicating with the interior of the receptacle when closed; and means for covering and uncovering said medium when the receptacle is open and closed respectively. 35
18. A receptacle having, in combination, a closure; a hygroscopic medium associated therewith; and means operative to cover said medium to exclude it from the atmosphere when the closure is open and to uncover said medium for exposure to the interior of the container when the closure is shut. 40
19. A receptacle having, in combination, a door; a chamber for a hygroscopic medium; and means for closing said chamber when the door is open and for opening said chamber to communication with the interior of the receptacle when the door is closed. 45
20. A receptacle having, in combination, a door or closure; a chamber for a hygroscopic medium communicable with the interior of the receptacle; a shutter for closing said chamber when the door is open; and means for operating said shutter to open said chamber to communication with the interior of the receptacle when the door is closed. 50
21. A receptacle having a removable closure and having a hygroscopic medium communicating with the interior of the receptacle and means controlled by the opening and shutting of the closure movable to position to shut off the hygroscopic medium from the air when the closure is removed from the mouth of the receptacle and movable to position to expose said medium in the receptacle when the closure is applied on the mouth of the receptacle. 55
22. A receptacle having a removable closure equipped with a hygroscopic medium exposed in the receptacle when closed, and means carried by the closure automatically operating to shut off said medium from the air when the closure is removed from the mouth of the receptacle. 60
23. A receptacle having a removable closure equipped with a hygroscopic medium, movable means carried by said closure shutting off said medium from the air when the closure is off from the mouth of the receptacle, and means controlled by the closing of said closure to move said movable means to position to expose said medium in the receptacle. 65
24. A receptacle closure equipped in its interior side with a hygroscopic medium and movable means shutting off said medium from the air and adapted to be moved to expose said medium. 70

In testimony whereof, we have signed our names to this specification.

ROBERT G. PECK.
ALBERT BROWN.
